Inventor: M. L. Webster,
by G. Kennedy, Attorney.

UNITED STATES PATENT OFFICE.

MELVIN L. WEBSTER, OF INDEPENDENCE, IOWA.

REINFORCED DISPLAY AND SHIPPING CASE.

Application filed December 11, 1924. Serial No. 755,269.

My invention relates to improvements in reinforced display and shipping cases, and the object of my improvement is to supply a case having an open top and a stepped bottom, for the display of packets of seed or other merchandise, and in which the parts of the case are made up of apposed compartments fitted together between side walls, to thus strengthen the case against both transverse and longitudinal strains so that in use for displaying goods, or while being transported, the case will have a maximum of resistance consistent with its weight.

This invention also constitutes an improvement upon my stepped compartment case, patented to me by United States Patent No. 1,460,185, issued June 26, 1923.

The above object I have accomplished by the means which are hereinafter described and claimed, and which are illustrated in the accompanying drawings, in which Fig. 1 is a perspective front elevation of my improved reinforced display and shipping case. Fig. 2 is a vertical section from front to rear of said case, and Fig. 3 is a perspective view of one of the compartment devices as separated from the case. Figs. 4, 5 and 6 are respectively plans or views of constituent parts of the case compartments developed on a plane before bending and assembling into united structures, and in which the dotted lines indicate lines of bending.

The case and its compartments shown are merely illustrative of the invention, as all may be considerably varied in shape, dimensions and otherwise without departing from my invention.

The side walls of the case shown at 1 have forwardly and downwardly inclined top edges and are imperforate, but creased obliquely parallel with their inclined top edges, so that the lower rear corner parts are adapted to swing inwardly toward each other when the case is to be contracted in dimensions for storage or transportation. These corner parts 2 serve as easel parts or supports to hold the case upright when extended, and in this use are braced and held apart by means of a swinging flap 10 hinged at 11 to the sloped or stepped bottom of the case. This feature is shown in my said pat-

ent, hence will not be mentioned further here.

The side walls 1-2, as also the compartments may be constructed from fiber board, whether solid or as shown, of cellular or corrugated material, being both light and inexpensive for the uses thereof.

The case has any desired or similar compartments arranged and assembled together in stepped relation. Each compartment has a low front ledge or wall 3, a higher rear wall 6, like side walls 5 and 7 with top edges sloped to conform to the abutting parts of the inclined top edges of the wall parts 1-2, and a bottom 4. The uppermost and rearmost compartment is similarly constructed with a higher rear wall 8 which extends upwardly to the upper rear angles of the wall parts 1-2.

These compartments may be apposed to fit together in a stepped relation between and fitting said side walls 1-2 as shown, and abutting edges may be sealed or connected together by means of sealing strips as at 12 and 13. To provide separating means between the side walls of each compartment, all the front and rear walls thereof may be apertured at 14 in line to receive a cord 15 therethrough, so placed as to divide the compartments fractionally, so that packets of different kinds of seeds may be kept separate therein.

While the compartments may have its walls and bottom joined in any suitable or convenient manner, I have shown in Figs. 4 to 6 inclusive blank parts cut appropriately to be bent along the dotted lines by creasing, to be assembled to make a compartment shown in Fig. 3. The arrangement of these parts is obvious. The parts 6 (or 8) provide the backs, the parts 5 and 7 (or 9) the ends, and the part 3 the front of each compartment, the parts 4 being the bottoms, with the abutting edges sealed by sealing strips. In this manner the ends and partitions of the case are doubled, so that this reinforcing makes the case very strong.

Having described my invention, what I claim as new, and desire to secure by Letters Patent, is:

A shipping and display case, composed of spaced side walls and a plurality of open topped receptacles secured therebetween in

stepped relation, each receptacle being composed of two plates, one plate furnishing a relatively high rear wall with a shaped and bent end tab to serve as a side closure, and 5 the other plate bent longitudinally to furnish a relatively low front wall and a bottom part, said front wall part having a shaped and bent end tab to serve as a side

closure opposite the first-mentioned side closure tab, said side closure tabs being secured to said side walls, and the abutting front and rear walls of the receptacles being secured together. 10

In testimony whereof I affix my signature.

MELVIN L. WEBSTER.
